UNITED STATES PATENT OFFICE.

RUDOLPH WELCKER, OF YONKERS, NEW YORK.

CONCRETE-MIXER.

1,182,065.

Specification of Letters Patent.

Patented May 9, 1916.

Application filed March 19, 1912. Serial No. 684,827.

To all whom it may concern:

Be it known that I, RUDOLPH WELCKER, a subject of the Queen of the Netherlands, residing at Bronx Manor, city of Yonkers, 5 county of Westchester, State of New York, United States of America, have invented a new and useful Concrete-Mixer; and I do hereby declare the following to be a full, clear, and exact description of the same.

10 The present improvements, in apparatus for mixing and delivering concrete materials, relate to new combination of parts whereby, in the preferred form, the one apparatus is employed to mix the concrete, 15 this being accomplished while the apparatus is being hauled to the point of use of the concrete, and to deliver the mixed material substantially at any point desired. The apparatus is also capable of being used not 20 only as a mixer and as a car but also as a bucket.

While my improvements may be embodied in different forms of apparatus, I prefer, as illustrated in the accompanying 25 drawings, to use a rotatable hollow body having car-wheels surrounding and secured thereto, this constituting a car, having a plurality of discharge and filling openings therein, and doors for said openings—thus 30 providing a car which may readily be filled at any point of its travel, be emptied at any point of its travel, and, when desired, lifted from the track, and its contents dumped at any desired point.

35 Referring to the accompanying drawings, Figure 1 shows a rear view (partly broken away) of my improved apparatus; Fig. 2 is an end view thereof; Fig. 3 is a fragmentary detail, showing the manner of attaching a wheel to the car; and Fig. 4 is a sectional view, on the line A—B of Fig. 1, 40 through a door and its housing.

The apparatus comprises a pair of conical casings P having smaller ends pointing inwardly and rigidly secured to a drum J. Flanged wheels C are secured to the curved sides of the casing by means of angular plates H (Fig. 3) riveted to said curved sides and to the wheels, the wheels 45 being adapted to support the apparatus and permit it to be rolled on the track O, as for instance, by means of a rope or cable N wound about the drum J and drawn in any convenient manner. The flared outer ends 50 of the drums are closed by circular end plates G provided with approximately sec-

tor-shaped openings covered by outwardly swinging doors F hinged, as at R, to the castings K on the end plates G of the apparatus.

At the side edges of each door are secured inwardly projecting guide-plates D which together with the door form a receiving hopper when the door is in uppermost position, and a discharge chute when the door is in lowest position, both as shown clearly in Fig. 1. The guide-plates D are inclosed and protected by housings E secured to the end plates G and projecting inwardly from said plate along the periphery of the drum, 65 these housings serving also as mixing blades when the apparatus is rotated by being rolled upon the track O.

In Fig. 4 the space between the plate D and housing E is shown exaggerated but 75 in practice this is made to fit snugly so that the joint between the two may be watertight to prevent the leakage of the water ingredient of the concrete when it is introduced into the casing.

80 The angular plates H may be provided with suitable openings for receiving the hooks of the hoisting chain M, or they may consist of segments between which the hooks may be received.

85 The operation of the device is as follows: The apparatus is placed with one of its doors F uppermost and this door opened to form a hopper into which the unmixed ingredients of the concrete or other desired material is introduced, as from the chute L, all of the doors F except the uppermost being closed. Either or both of the casings may be filled in this manner. Then all of the doors are closed and the apparatus 90 rolled upon the track O to the point of discharge, the rotation of the casings and the revolution of the housings E causing the ingredients to be thoroughly mixed during 95 transit.

If the concrete is to be discharged at a point at the side of the track, the apparatus is rolled until the lowermost door F is at or near this point and the door opened, thus 100 discharging the material as shown in Fig. 1. If the concrete is to be discharged at a point some distance from the track, the apparatus is rolled to a convenient point on the track and then hoisted to the desired point by means of the hooks and chain M 110 and a suitable crane or other hoisting device. The apparatus may be used also for

transporting already mixed concrete, in which case the rotation of the casings prevents the separation by gravity of the heavier from the lighter ingredients.

5. I claim:

1. A concrete mixer comprising a rotatable conical casing provided with a plurality of openings near the most eccentric part of the larger end portion; outwardly swinging doors, one for each opening, and each rotatable with the casing and hinged thereto at the edge of the door nearest the axis of the casing.

15. A concrete mixer comprising a rotatable casing adapted for horizontal rolling displacement and having an eccentrically arranged opening in the end thereof; and a door for said opening hinged at its inner edge to and rotatable with said casing and adapted to serve as a hopper to direct material into the casing when said opening is uppermost.

25. A concrete mixer comprising a freely rolling rotatable casing having an inclined bottom adapted to direct material to an end of the casing, the casing being provided with openings in the most eccentric part of said end; and outwardly swinging doors one for each opening hinged to the casing and at the inner edge of the door and rotatable within the casing.

35. A concrete mixer comprising a freely rollable casing having a part adapted to deflect material toward an end of the casing; an eccentrically arranged opening in said end; a door for said opening; and wheels between the ends of the casing.

40. A concrete mixer comprising a rotatable freely rolling casing having a conical part adapted to deflect material toward an end of the casing; an opening near the most eccentric part of said end; a door for said opening and rotatable with the casing; and wheels co-axial with the casing and disposed between the ends thereof.

45. A concrete mixer comprising a pair of co-axial conical casings having their smaller ends secured together and each provided with a plurality of openings in the most eccentric part of their outer ends; and outwardly swinging doors, one for each opening, each rotatable with the casing and hinged to it at the edge of the door nearest the axis of the casings and a pair of wheels placed around the casing intermediately of the ends thereof.

55. A concrete-mixer comprising a rotatable body having an eccentric opening in the end thereof, and a door fitted to said opening, said door being hinged rotatable to the body along the edge of the door nearest the axis of rotation of the body and provided with plates, for guiding the discharging concrete when the opening is at its lowermost position and for guiding the entering in-

gredients when the opening is in a higher position.

8. A combined car and concrete-mixer comprising a rotatable body having two carrying and mixing compartments each flaring outwardly toward the outside of the car and each having a plurality of filling and discharging openings and each having doors for said openings, in combination with car-wheels surrounding and secured to said body.

10. In a concrete mixer, the combination of a pair of horizontally disposed substantially cone-shaped casings having their smaller ends pointing inwardly; wheels secured to and co-axial with the casings; end plates secured to and closing the outer ends of the casings and provided with eccentric openings; and outwardly opening doors hinged to the edges of the respective openings.

15. In a concrete mixer, the combination of a pair of horizontally disposed substantially cone-shaped casings having their smaller ends pointing inwardly; a drum fastened between said inner ends and holding the casings in alinement; wheels secured to and co-axial with the casing; end plates secured to and closing the outer ends of the casings and provided with eccentric openings; and outwardly opening doors hinged to the inner edges of the respective openings.

20. In a concrete mixer, the combination of a pair of horizontally disposed truncated cone-shaped casings having their smaller ends pointing toward each other; a drum fastened to and interposed between said smaller ends and holding said casings and drum in alinement; wheels disposed around the intermediate part of said casings co-axial therewith; end plates secured to and closing the outer ends of said casings and having approximately sector shaped openings therein remote from the axis of the casings; and outwardly opening doors adapted to cover said doors and hinged at the inner edges of the openings.

25. A concrete-mixer comprising a rotatable body having an eccentric opening in the end thereof, housings extending into said body and constituting mixing blades, and an outwardly swinging door fitted to the said end and formed to movably fit within the housings aforesaid.

30. In a concrete mixer, the combination of a rotatable casing having an opening in the end thereof; a door for said opening; inwardly projecting guide plates on said door; and mixers on the inner face of said end and projecting into the casing and forming protections for the guide plates when the door is closed.

35. In a concrete mixer, the combination of a rotatable casing; end plates secured thereto and having openings therein; combined housings and mixers of approximately U-shaped cross-section secured to the side

edges of said openings and outwardly opening doors for said openings; and guide plates secured to said doors and slideable on said housings respectively.

15. In a concrete mixer, the combination of a rotatable casing provided with openings; outwardly opening doors for said openings and hinged to said rotatable casing; inwardly projecting guide plates on 10 said doors; and mixers secured to said casing and adapted to receive said plates when the doors are closed.

16. In a concrete mixer, the combination of a rotatable casing having openings in the 15 ends thereof; outwardly opening doors hinged at their inner ends to said casing and forming covers for said openings respectively; and guide plates on the inner faces of said doors and perpendicular thereto, and forming hoppers when the doors are 20 opened.

17. In a concrete mixer, the combination of a pair of horizontally disposed substantially cone shaped casings having their 25 smaller end turned inwardly and secured together; wheels disposed about the casings; end plates secured to the larger ends of the casings and provided with openings near the edge thereof; outwardly opening doors 30 for said openings and hinged at their inner ends; guide plates on the sides of said doors and projecting inwardly into the casing; and mixers secured to the inner face of said 35 ends and projecting inwardly into the casing and adapted to receive said guide plates when the doors are closed.

18. In a concrete mixer, the combination of a pair of horizontally disposed substantially cone shaped casings having their 40 smaller end turned inwardly and secured

together, wheels disposed about the casings; end plates secured to the larger ends of the casing and provided with openings near the edge thereof; outwardly opening doors for said openings and hinged at their inner 45 ends; guide plates on the sides of said doors and projecting inwardly into the casing; and mixers secured to the inner face of said ends and projecting inwardly into the casing and adapted to form protections for said 50 plates when the doors are closed.

19. In a concrete mixer, the combination of a pair of horizontally disposed truncated cone shaped casings having their smaller 55 ends pointing toward each other; a drum fastened to and interposed between said smaller ends and holding said casings and the drum in alinement; wheels disposed about the intermediate part of said casings co-axial therewith; end plates secured to and closing the outer ends of said casings and having approximately sector shaped openings therein; combined housings and mixers of approximately U-shaped cross sections 60 secured to the inner face of said end plates perpendicular thereto, at each side edge respectively of said openings; a spider at the center of each end plate; doors, one for each opening, hinged to said spider and covering said openings respectively; and end plates 65 secured to the side edges of said plates perpendicular to the plates and slidably received in the housings.

In testimony whereof, I have signed my name to this specification in the presence of 75 two subscribing witnesses.

RUDOLPH WELCKER.
